UNITED STATES PATENT OFFICE.

FRANCIS A. JIMERSON, OF ATHENS, PENNSYLVANIA, ASSIGNOR TO INGERSOLL-RAND COMPANY, OF JERSEY CITY, NEW JERSEY, A CORPORATION OF NEW JERSEY.

BUILT-UP CRANK SHAFT.

Application filed May 27, 1922. Serial No. 564,100.

To all whom it may concern:

Be it known that I, FRANCIS A. JIMERSON, a citizen of the United States, and a resident of Athens, county of Bradford, 5 State of Pennsylvania, have invented a certain Built-Up Crank Shaft, of which the following is a specification accompanied by drawings.

This invention relates to built up crank 10 shafts for fluid actuated multi-cylinder engines, and the objects of the invention are to simplify and strengthen such crank shafts, obtain better balance and more perfect alignment of the bearings, and permit 15 the use in the engine of solid end connecting rods, rather than multiple piece connecting rods or those of the toggle type. Another object of the invention is to enable 20 the parts to be readily assembled and disassembled.

A further object of the invention is to provide the bearing portions of the crank pins in the form of sleeves carried by the center web of the crank shaft, through 25 which sleeves the crank pins are inserted.

To all of these ends the invention is shown in one of its preferred forms in the accompany drawings, in which—

Figure 1 is a side elevation partly in 30 longitudinal section of an assembled crank shaft.

Figure 2 is an end view of Figure 1.

Figure 3 is a transverse sectional view 35 of Figure 1 on the line 3—3 looking in the direction of the arrows,

Figure 4 is a side elevation of one of the end webs with its crank pin,

Figure 5 is a longitudinal sectional elevation 40 of the center web and sleeve portions, and

Figure 6 is a side elevation of the other end web and crank pin.

Referring to the drawings, the crank shaft comprises the center web A having 45 sleeve portions B integral therewith and extending outwardly in opposite directions at each end of the web to form the bearing portions of the crank pins C, which are adapted to be inserted through the sleeve portions and secured to the webs as by means 50

of the nuts D. Suitable keys E are also provided for keying the crank pins C in the sleeve portions B.

The shaft ends F and G are provided with end webs H and J with which the 55 crank pins C are integrally formed. The shaft ends carry the main bearings K and L shown in this instance as ball bearings, and the shaft end F also carries the driving pinion O. The end webs H and J may 60 also be provided with the counter weights P and Q.

In accordance with my construction, the crank pins are provided with sleeve bearing portions B which not only serve the 65 usual functions of bearings, but act as spacing members for spacing apart the webs of the crank shaft and add to the strength of the entire structure. The crank pins are readily inserted into the sleeve bearing 70 portions B or withdrawn therefrom, and are securely held in position in a simple manner when the parts are assembled.

I claim:

1. A built up crank shaft for multi-cylinder engines, comprising a center web having sleeve portions integral therewith and extending outwardly in opposite directions at each end of the web to form the bearing portions of the crank pins, shaft ends 80 having end webs carrying crank pins integral therewith and adapted to be inserted through said sleeve portions of the center web, and means for securing the crank pins to the center web. 85

2. A built up crank shaft for multi-cylinder engines, comprising a center web having sleeve portions integral therewith and extending outwardly in opposite directions at each end of the web to form the bearing 90 portions of the crank pins, shaft ends having end webs carrying crank pins integral therewith and adapted to be inserted through said sleeve portions of the center web, keys for keying the crank pins in the 95 said sleeve portions, and nuts for securing the crank pins to the center web.

In testimony whereof I have signed this specification.

FRANCIS A. JIMERSON,
